Term of patent 14 years

(Cl. D74—1)

Fig. 2.

Fig. 1.

Fig. 3.

FIGURE 1 is a front elevational view of a holder for a television program or the like embodying our design; FIGURE 2 is a top plan view of the holder; and

The characteristic features of our design reside in the upright but slightly inclined position of and the disparity in height between the substantially triangular shaped front and back wall members of the holder all as shown.

We claim:

The ornamental design for a holder for a television program or the like, as shown and described.
